CLAIM

The ornamental design for a three internal element LED bulb, as shown and described herein.

DESCRIPTION

FIG. 1 is a front, top perspective view of a three internal element LED bulb, according to one example of the present disclosure, including an at least partially translucent bulb surface revealing interior elements with the three internal element LED bulb in a “powered-off” state;

FIG. 2 is a front, top perspective view of a three internal element LED bulb, according to one example of the present disclosure, including an at least partially translucent bulb surface revealing interior elements with the three internal element LED bulb in a “powered-on” state;

FIG. 3 is an exploded view illustrating interior elements of the three internal element LED bulb of FIG. 1, according to one example of the present disclosure;

FIG. 4 is a right side view of the three internal element LED bulb of FIG. 2;

FIG. 5 is a back plan view of the three internal element LED bulb of FIG. 2;

FIG. 6 is a left side view of the three internal element LED bulb of FIG. 2;

FIG. 7 is a front plan view of the three internal element LED bulb of FIG. 2;

FIG. 8 is a top plan view of the three internal element LED bulb of FIG. 2; and,

FIG. 9 is a bottom plan view of the three internal element LED bulb of FIG. 2.
